UNITED STATES PATENT OFFICE.

J. FAIRFIELD CARPENTER, OF BERLIN, GERMANY.

AUTOMATIC ELECTRIC AIR-BRAKE.

SPECIFICATION forming part of Letters Patent No. 359,593, dated March 22, 1867.

Application filed November 10, 1886. Serial No. 218,503. (No model.)

To all whom it may concern:

Be it known that I, J. FAIRFIELD CARPENTER, a citizen of the United States, residing at the city of Berlin, in the Kingdom of Prussia, German Empire, have invented certain new and useful Improvements in Automatic Electrical Air-Brakes, of which the following is a specification.

The object of this invention is to provide efficient means for operating pneumatic brakes by electrical apparatus, the prime purpose of the invention, in common with inventions having a like object, being to set the brakes on all the cars of a train regardless of the number of cars composing the train at practically one and the same instant, so as to avoid the succession of shocks that would occur by the cars coming in contact if any appreciable lapse of time occurred between the setting of the brakes on the cars.

The invention consists in a valve or valves of peculiar construction; also, of novel combinations of a valve with pneumatic brake mechanism, all as I will hereinafter particularly set forth and claim.

In the accompanying drawings, in the several figures of which like parts are similarly designated, Figure 1 is a sectional view illustrating my invention as applied to the Westinghouse automatic brake. Fig. 2 is a similar view of my invention applied to the ordinary English and Europeau vacuum-brake system. Fig. 3 is a similar view of my invention applied to the Eames vacuum-brake system.

Fig. 4 is a vertical section of one form of coupling; Fig. 4^a, a similar view of another form of coupling. Fig. 5 is a sectional elevation showing my invention applied to a combined reservoir and brake-cylinder. Figs. 6 and 7 are sectional views of two forms of my valve. Fig. 8 is a sectional view of my two-valve electro-pneumatic-brake system. Fig. 9 is a sectional view of another form of my valve. Fig. 10 shows in front, side, and top view a form of cock for controlling the air and electric systems. Fig. 11 is a section and plan of another form of coupling; and Fig. 12 is a side elevation of the air-pipe cut-off cock, showing the arrangement of the electric conductors thereon.

In practicing my invention I make use of any of the well-known systems of pneumatic brakes or of modifications thereof, and in ap-

plying my invention thereto I am enabled to operate the brakes by electricity or by the use of the motor-fluid, or by employing both simultaneously.

I will first describe the construction of my valve and then proceed to describe several modes of applying it in pneumatic-brake systems; and, first, then, as to the valve. Referring to Figs. 6, 7, and 9, wherein the details of the valve are illustrated, I have shown said valve having as essential features an outlet to the external atmosphere, communication with the line of pipes for conveying the motor-fluid from one car to another, and an electrically-operated valve. In Fig. 7 the simplest form of this valve is shown, and it comprises a shell, 1, of suitable shape, having nipples *b b*, for connection with the pipes, and provided with an outlet, 2, to the external atmosphere. The inner face, 3, of this outlet is formed as a valve-seat, and within this outlet, and seated upon said seat, is a winged valve, *a*. The stem of this valve *a* is extended up into the shell, and is provided with a metal plate, *e*, made fast thereto, and the valve is kept seated normally by means of a coiled spring, 4, bearing upon the plate *e*. Suspended within the shell 1 is a magnet, *d*, having suitable connections, 5, with a source of electricity. This magnet, when energized, attracts the plate *e* and unseats or lifts the valve *a* to open communication to the atmosphere. The plate *e*, therefore, is, in fact, an armature, 85 and will be so referred to hereinafter.

I prefer to use a dynamo or battery on the engine as the source of electricity, and I pass conductors, if desired, through the lines of pipes, so as to make a circuit throughout the train, and I put these immediately under the control of the engineer. Now, if a train be equipped with the Westinghouse system of automatic air-brakes, comprising the usual main reservoir, air-compressor, and the customary appurtenances on the engine, together with the usual lines of pipe and the brake-cylinder, auxiliary reservoir, and triple valve for each car, my valve may be applied to operate the air system to set and release the brakes. I have shown such combination in Fig. 1. *a*^x may represent my electrically-operated valve arranged in the branch pipe connecting the main pipes with the triple valve

b^x. A is the brake-cylinder, and B the auxiliary reservoir. The operation of this form of brake mechanism, being perfectly well known, need not be further described; but it needs to be said that the valve *a^x*, being placed in a pipe normally under pressure, is operated by the application of the electric current to the magnet therein to unseat the valve *a* and permit the escape of the pressure into the atmosphere. This, as understood, minimizing or taking off the pressure from the under side of the piston in the triple valve, opens the outlet from the auxiliary reservoir to the brake-cylinder and applies the brakes. When the electric circuit is broken, the valve *a* is seated, and, the pipe-lines being thus closed, the fluid-pressure can be re-established at any time, raising the triple valve, thus releasing the brakes and recharging the auxiliary reservoir.

Operating the valve *a^x* in Figs. 2 and 3 in the vacuum systems therein shown, so as to let the air into the main pipes, will serve to set the brake in the usual way, and by letting out the air the brakes will be released as usual. Now, in all of these three systems of operating brakes by pneumatic pressure in conjunction with my electrically-operated valve it is possible to work the valves electrically or pneumatically, or by a combination of the two; hence a train equipped with my apparatus can be held under the most perfect control at all times, no matter what the number of cars composing it nor the grades on which it is traveling.

A good form of cock for controlling the electric circuit and the fluid-pressure is shown in the three views of Fig. 10. The internal mechanism of this cock is as usual. Its handle *x*, however, is provided with a spring-lever, *x'*, which engages a notch in the head of the plug to lock said lever to the plug, and cause the plug to turn with the lever when it is moved, it being understood, of course, that when said lever *x'* is disconnected from the notch the handle *x* is free to turn without turning the plug. The handle *x* has an electric contact-piece, *x²*, which finds its counterpart at *x³* on the cock-shell, and said contact *x³* is connected with the circuit-wires including the electro-magnetic valves. Now, it will be seen that when the valves are to be operated electrically, the handle *x* is disconnected from the plug and contact made between contacts *x²* and *x³* to close the circuit and open the valves. So, also, it will be seen that when the plug is to be operated to control the fluid-pressure, the handle is turned just short of bringing the contacts against each other; and, again, when electricity and fluid-pressure are to be combined for operating the valves, then the handle *x* is connected with its plug and the contacts *x²* *x³* brought against each other, the plug being at such times closed, and the electric-circuit also closed.

In coupling a brake system in accordance with my invention I prefer to run the electric conductors through the air-pipes and to utilize

the metal heads of the couplings as electric conductors. I therefore connect the wires with the metal heads in such way as that when the current is established the couplings will be electrified.

Figs. 4, 4^a, and 11 serve to illustrate this feature. The lines *m* and *n* indicate the conductors; and in this connection I may also describe my mode of carrying the conductors around the cock usually placed in the ends of the air-pipes to close them when the train is to be broken up. I lead the wires through the rubber hose, and where the hose is jointed to the coupling I let the wires project between the hose and the coupling and extend outside of and around the cock; or the wires may be passed out through the metal connections through hollow screws, as indicated at the left-hand side of Fig. 12. When the hose has to be renewed, the wires are disconnected at the side screws, having only a butt-connection, and then a new piece supplied with wires, being brought into position, the projecting ends of the wires may be readily connected by any unskilled person to the projecting ends of the wires left connected with the cock.

In Fig. 6 I have shown a valve which is designed to subserve the purposes in some relations of both my valve, already described, and the triple valve. In this valve the inlet *b'* and outlet *b²* will usually be at different altitudes, and on the stem *g* of the valve I arrange a piston or diaphragm, *f*, supporting it by means of a spring, *f'*, in a position which normally shuts off communication between the inlet and outlet. The magnet *d* and the armature *e* are arranged with relation to the valve *a* substantially as in the other form shown in Fig. 7, and so far as the operation of opening and closing the outlet to the atmosphere is concerned this valve is the same as that shown in Fig. 7; but the piston or diaphragm *f* forms another opening or port, and under certain circumstances a valve, as I will now describe. When the armature *e* is lifted and the valve *a* thereby unseated, it will be noticed that the head *g'* is raised from the opening in the piston or diaphragm *f*, allowing the air to escape through said piston into the air. Whether the port 2 be closed or not, if at any time the pressure on the upper side of the piston or diaphragm *f* is greater than the pressure on its under side, then said piston will be moved downwardly to uncover its opening and admit the incoming air below it and into the reservoir or brake-cylinder, as the case may be, so that by the use of this valve not only can the brakes be applied and held, but at the same time the supply of fluid-pressure to the reservoir can be replenished.

In order to facilitate distinguishing the two forms of valves shown in Figs. 6 and 7, respectively, I have designated such valves D and F, respectively.

In Fig. 5 I have shown a form of brake apparatus for use especially in conjunction with the valve D. A represents the brake-cylin-

der; B, the reservoir; C, a piston, and E a piston-rod, which is connected with the brake at one end and at the other end with the piston C. The valve D is connected to one end 5 of the brake-cylinder by its outlet b^2 . In operating with this form of brake apparatus air-pressure from the main pipe l enters at b' , pressing down the piston f , and, passing through the valve g , enters the brake-cylinder A through 10 pipe b^2 , and, pressing against the brake-cylinder piston C, moves it into the position shown, and then passing over the same (the cupped leather packing of the piston offering little resistance in this direction) fills the auxiliary 15 reservoir B. If, now, an electric current is sent through the magnet, the whole valve mechanism $a e f g$ will be lifted, so that the pressure in the cylinder A will escape through the opening 2 and the compressed air in the reservoir B, 20 which cannot return over the piston C, (the leather in the piston being cupped the other way,) will expand, forcing the piston C toward the other end of the cylinder and applying the brakes. If instead of the electric current air- 25 pressure had been let out of the main pipe l , the piston or diaphragm f , together with the valve a , would have been lifted by the pressure under it from the cylinder A, and the air from the cylinder A would have escaped through the port 2, 30 effecting the same result as before. In either case, to release the brake fresh pressure from the engine moves down the piston f , and, the valve a being closed, enters the cylinder A through pipe b^2 , and, driving back the main 35 piston C, releases the brake, as has been shown. Thus the brake arrangement shown in Figs. 5 and 6 is capable of being applied by air-pressure alone, by electricity alone, or by both combined. This form of apparatus, therefore, could 40 be used on Westinghouse trains, whether the same were fitted with the additional electrical apparatus above described or not. In long trains, however, and also where quickness of action and minimum of air consumption and 45 the ability to brake down long grades without once releasing the brake are desiderata, the apparatus shown in Fig. 8 possesses special advantages. In this form of apparatus a brake-cylinder, A, is used, and also an auxiliary reservoir, B, and connections with the main pipe l , and I employ between the main pipe and the auxiliary reservoir my valve D, and connect said valve D at its opening 2 by 50 means of a branch pipe, l' , with the inlet to my valve F, which valve F, I interpose between 55 said branch pipe and the brake-cylinder in substantially the arrangement shown. In this form of apparatus each valve is supplied with an independent electrical circuit for operating 60 the same. Now, it will be seen that by working the valve D either by electricity or air, or both, the pressure in the auxiliary reservoir will pass into the brake-cylinder and operate the brake, and that during this operation 65 the air will pass from the main reservoir at the engine through the valve D into reser-

voir B, thus keeping up the pressure therein without in the least disturbing the flow of air from the reservoir B through the branch pipe and valve F into the brake-cylinder, so that 70 the brakes may be held on or set for any length of time on long downgrades; and this feature I believe to be one of great importance in the operation, more especially of freight trains supplied with automatic pneumatic brakes. 75 Heretofore it has been customary to release the brake periodically, in order to replenish the auxiliary reservoir. With this arrangement no auxiliary brakes—such as steam or vacuum—are needed on the engine. 80

In the form of apparatus shown in Fig. 8 to release the brakes, the valve D is closed and the valve F is opened, whereby the air-pressure is let out of the brake-cylinder. 85

In Fig. 9 I have shown a further modification of my electro-pneumatic valve. In this valve I employ the piston or diaphragm f , as before, the spring f' , the valves a and g , and the inlet b' , and outlet b^2 ; but I modify the construction of the armature e in substance as 90 follows: I divide this armature into two parts, e and e' , the latter arranged to rise and fall within a recess, e^2 , made in the face of the main armature, and between the main armature and the part e' , I interpose springs e^3 , 95 which normally hold the plate e' elevated. I also employ two magnets, d and d^3 , the former arranged to co-operate with the plate e and the latter to co-operate with the plate e' ; but I place these two armatures in one and the 100 same circuit, and, inasmuch as the springs e^3 normally hold the plate e' somewhat above the level of the upper face of the plate e , the magnet d^3 in point of time operates somewhat in advance of the magnet d , and hence gives a 105 preliminary lift to the valve, which is completed by the magnet d , thereafter acting upon and lifting the armature e . In this way the lift of the valve is divided between these magnets, thus reducing the distance of the magnets from their armatures by one-half and greatly increasing their power. The stem of the valve extends up through the plates e and e' , and is surrounded by a sleeve, e^4 , and provided with a head or nut, e^5 . The sleeve e^4 110 rests upon the plate e within the recess e^2 , and the plate e' encircles said sleeve. The plate e' acts directly upon the head e^5 to lift the valve, while the plate e acts upon the sleeve e^4 for the same purpose, the said sleeve bearing 115 on its upper surface against the under surface of the said head e^5 . 120

Referring to Figs. 4, 4^a, and 11, it should be said that the act of coupling up the hose makes electrical contact on both lines of conductors 125 or wires. The conductor m is completely insulated from the coupling in any well-known way, while the conductor n is in electrical contact with the coupling, but insulated from the air-pipes by being carried through the rubber 130 hose p .

It may be here remarked that the passing of

the conductors around the stop-cock, as shown in Fig. 12, is useful when automatic couplings are not used.

What I claim is—

5. 1. A valve for automatic pneumatic brakes for railway-cars, comprising a suitable shell having an inlet and outlet and an opening, 2, to the atmosphere, a valve seated in said opening and provided with an attached plate, *e*, to which serves also as an armature, and a magnet arranged in an electric circuit, substantially as described.
15. 2. A valve for automatic pneumatic brakes for railway-cars, comprising a suitable shell having an inlet and outlet and an opening to the atmosphere, a valve seated in said opening, an armature connected to said valve and consisting of two independent but connected plates, and magnets for operating said two-part armature independently, and an electric circuit in which said magnets are arranged, substantially as described.
25. 3. A valve for automatic pneumatic brakes for railway-cars, comprising a suitable shell having an inlet and outlet and an opening to the atmosphere, a valve seated in said opening and provided with a plate, which serves also as an armature, and a magnet arranged in an electric circuit, and a piston or diaphragm interposed between the inlet and outlet between the armature and the opening to the atmosphere, substantially as described.
35. 4. A valve for automatic pneumatic brakes for railway-cars, comprising a suitable shell having an inlet and outlet and an opening to the atmosphere, a valve seated in said opening to open and close it, a piston or diaphragm interposed between said inlet and outlet and provided with a port, a valve in said port connected with the valve in the opening to the atmosphere, and one or more armatures connected to said valve, and magnets arranged in the electric circuit, the whole adapted to be operated by the electric current, by pneumatic pressure, or by the two combined, substantially as described.
45. 5. In a pneumatic-brake system, a brake-

cylinder and a reservoir, combined with the main air-pipes, an electro-pneumatic valve interposed between said reservoir and main air-pipes and opening into a branch pipe extending to the brake-cylinder, and a second electro-pneumatic valve interposed between the brake-cylinder and the first-named valve, and independent electric circuits for the said valves, substantially as described.

6. In a pneumatic-brake system, a brake-cylinder and reservoir and the main line of air-pipes, combined with a valve, *D*, interposed between the reservoir and air-pipes and having a valve arranged in a piston or diaphragm for admitting air from the main air-pipes into the reservoir, and a second valve arranged in the outlet communicating directly with the brake-cylinder to permit the flow of air from the reservoir to the brake-cylinder to set the brakes, and a valve, *F*, interposed between the brake-cylinder and the first-named valve to release the brakes, substantially as described.

7. In an electro-pneumatic-brake system, a reservoir and brake-cylinder, main air-pipes, one or more electro-pneumatic valves in said air-pipes and interposed between the reservoir and brake-cylinder, and an open electric circuit, combined with a regulating-cock arranged in said air-pipes and electric circuit and having a contact-point of the circuit-wires, and an operating-handle detachably connected with the plug of said cock and adapted to be disconnected from the plug and be brought into metallic contact with the contact-point of the cock to close the circuit without moving the air-cock, and to be connected to the plug to operate it to control the supply of air without closing the electric circuit, and also adapted to be connected with the cock and close the circuit to put in use both the electric circuit and the air, substantially as described.
